United States Patent Office

Des. 219,427
Patented Dec. 15, 1970

219,427

DECANTER

Robert Rieb, New York, N.Y., assignor, by mesne assignments, to John Bardenheier Wine & Liquor Company, St. Louis, Mo., a corporation of Missouri

Filed Nov. 3, 1969, Ser. No. 19,887

Term of patent 14 years

Int. Cl. D9—01

U.S. Cl. D9—160

FIG. 2

FIG. 1

FIG. 3

FIG. 4

FIG. 1 is a front elevational view of a decanter, showing my new design;

FIG. 2 is a top plan view thereof;

FIG. 3 is a side elevational view thereof; and
FIG. 4 is a bottom view thereof.

I claim:

The ornamental design for a decanter, substantially as shown.
